UNITED STATES PATENT OFFICE.

LE ROY A. CRUMLEY, OF NEW YORK, N. Y., ASSIGNOR TO ISRAEL J. TOMBACHER, OF NEW YORK, N. Y., AND HARRY M. FELTENSTEIN, OF CHICAGO, ILLINOIS, DOING BUSINESS UNDER NAME AND STYLE OF M. EISENBERG & SON.

DESIGN FOR A LIGHTING-FIXTURE BODY.

Application filed March 16, 1926. Serial No. 16,942. Term of patent 3½ years.

To all whom it may concern:

Be it known that I, LE ROY A. CRUMLEY, a citizen of the United States, and a resident of the city of New York, county of Bronx, and State of New York, have invented a new, original, and ornamental Design for a Lighting-Fixture Body, of which the following is a specification, reference being had to the accompanying drawing, forming a part thereof.

Figure 1 is a side elevational view of the lighting fixture body; and

Figure 2 is an inverted plan view of the same.

I claim:

The ornamental design for a lighting fixture body substantially as shown.

LE ROY A. CRUMLEY.
